United States Patent Office.

FRANK REED, OF FITCHBURG, MASSACHUSETTS.

Letters Patent No. 97,694, dated December 7, 1869; antedated November 30, 1869.

IMPROVEMENT IN PRIVY-SEATS.

The Schedule referred to in these Letters Patent and making part of the same.

To all whom it may concern:

Be it known that I, FRANK REED, of Fitchburg, in the county of Worcester, and State of Massachusetts, have invented a new and useful Improvement in Privy-Seat; and I do hereby declare that the following is a full, clear, and exact description thereof, which will enable those skilled in the art to make and use the same, reference being had to the accompanying drawings, forming part of this specification.

This invention relates to a new and useful improvement in seats for privies or water-closets; and also portable privy-seats for the sick-chamber; and

It consists in providing the seat with an adjustable cover, or extra seat, and with a closing valve and their operating-mechanism, arranged as will be hereinafter described.

The drawing represents a perspective view of a privy-seat, constructed according to my invention.

A is the seat of the ordinary privy.

B is the adjustable extra seat, which is secured to a shaft over the seat A, as seen in the drawing.

C represents the valve which closes the hole in the seat A from the under side, its size or diameter being seen in dotted lines.

This valve and the extra seat B are operated simultaneously.

When the seat is down, the valve drops, and *vice versa*.

The manner in which they are operated, is as follows:

Under the seat A there is a horizontal shaft, D, as seen where the seat is broken away, upon which are two pinion-wheels e f.

The seat B is attached to a shaft, g, which is supported on the seat by journals at its ends, as seen at h i.

On this shaft there is a pinion, j.

k is a double rack, which engages with the pinion j, and also with the pinion e.

L is a sector-bar, having a rack on its end which engages with the pinion f.

m is a spring which bears upward against the sector-bar with a constant pressure.

When the bar is depressed, it will be seen that the shaft D, and also the shaft g, will be partially revolved.

The revolution, or partial revolution of the shaft g, brings the seat B down on to the seat A, and the partial revolution of the shaft D, to which the valve C is attached, brings the valve upward against the bottom of the seat A.

As before stated, when the hole in the seat A is closed by the valve, the seat B is raised, as seen in the drawing.

The sector-bar L is depressed by a weight applied to the tread-piece N, through the connecting-rod O.

This tread-piece may be a portion of the floor, or a piece on the floor, to which the rod O is attached.

The seat B may be made of either wood or metal, covered with carpet or baize cloth, or cushioned in any desired manner, so as to avoid the inconvenience and discomfort of sitting on a cold or frosty seat.

To delicate persons or invalids, in country privies, this is a matter of great importance.

As seen in the drawing, the seat is in the condition in which it always remains, except when in actual use.

A person steps upon the tread-piece N, which brings the seat B down, and drops the valve C.

The sector-bar receives sufficient weight from the person, to keep it depressed.

When the person rises, the spring operates to throw it up, thereby closing the hole and elevating the seat B.

These seats are admirably adapted to the sick-room, as the seat-box may be made perfectly tight, and so that the chamber-vessel may be introduced through a door in the side.

The valve will prevent the escape of all disagreeable odor.

I claim as new, and desire to secure by Letters Patent—

1. The shaft D, with its pinions e and f, the sector-bar L, spring m, rod o, and tread-piece N, in combination with privy-seat, substantially as described and for the purposes set forth.

2. The combination of the shaft g, pinion j, and double rack k, with the shaft D, carrying the valve C, and operated as described, and with the extra seat B, as herein set forth for the purpose specified.

FRANK REED.
